UNITED STATES PATENT OFFICE

2,538,128

RINGTOSS TYPE GAME BOARD

Oscar C. Simmons, Dallas, Tex.

Application February 13, 1948, Serial No. 8,185

1 Claim. (Cl. 273—104)

1

This invention relates to a game board construction, and more particularly, has reference to a game board of the type that supports upwardly extended pins, the object being to ring the pins with any of a plurality of rings thrown by a player.

An important object of the invention is to provide a game board of the type stated wherein it is possible to vary the location of the pins in a manner to permit various types of games to be played, and also to permit variation of the degree of difficulty, so that by selective location of pins, it is possible to require more or less skill, as desired, on the part of the player.

Another object is to provide a board of the type stated whereby the pins can be adjusted to angular positions, again for the purpose of playing different games or requiring more or less skill, this being possible either alone or in combination with the above-mentioned varying of pin positions on the board.

Still another object is to provide a game board of the type stated which will embody, in cooperation with the pins supported thereby, a centrally disposed pocket, it being possible to play a game in which both pins and pocket play a part, or in which either pins or pocket are used alone, at the option of the players.

Still another object is to provide a game board in which the pins are removable, so that all or part of the pins can be used as desired, this being an added variation possible to be used either alone or in combination with those mentioned above, for the purpose of placing a greater or smaller premium on skill.

Another important object is to provide a board of the type stated which can be used at any location, either indoors or outdoors, can be supported on legs, or positioned flat on a supporting surface, whichever is desired, it being additionally possible to position the board at an incline.

Another important object is to provide a game board construction which will be exceptionally durable, readily manufactured and set up, and which is capable of being produced at low cost.

With the foregoing and other objects in view which will appear as the description proceeds, the invention consists of certain novel details of construction and combinations of parts, herein-after more fully described and pointed out in the claims, it being understood that changes may be made in the construction and arrangement of parts without departing from the spirit of the invention as claimed.

Referring to the drawing:

2

Figure 1 is a top plan view of a game board constructed in accordance with the invention.

Figure 2 is a section taken substantially on line 2—2 of Figure 1.

5 Figure 3 is a fragmentary elevational view, on an enlarged scale, of one of the pins, a plate member secured to the pin being shown in section.

Referring to the drawing in detail, the reference numeral 5 designates a flat board, preferably circular formed with a large central opening 6. Opening 6 provides access to a depending mesh pocket 7, secured to the under side of the board by means of a retaining ring 8, nails 9 or similar fasteners passing through the retaining ring and top of the pocket, and into the board 5.

An outer annular series of openings 10 is formed in the board 5, this series being preferably disposed close to the marginal edge of the board. Another annular series of openings 11 is also provided, this being an inner series disposed close to the edge of the central opening 6.

Long pins 12 and short pins 13 are removably mounted in openings 10 and 11, and can be arranged as desired. For example, all the long pins 12 can be disposed in openings 10, with all the short pins 13 being disposed in openings 11. Or, the short pins can be mounted in the outer series of openings with the long pins mounted in the inner series. Or, and as shown in the drawing, long and short pins can be alternately positioned in the outer series of openings 10, with a similar arrangement in the inner series. Other arrangements may well suggest themselves.

The pins 12 and 13 are not only removably mounted in openings 10 and 11, but also can be rotated therein, for a purpose which will appear.

Referring to the construction of the long pins, each is provided with a base 14 formed with a stop flange 15 spaced from the bottom end thereof. In this way, base 14 can be mounted in an opening with stop flange 15 engaging the upper surface of the board 5.

At its upper end, base 14 is formed at one side with an upwardly extended ear 16, the top portion of which is half round as best shown in Figure 3. Each pin 12 also includes a pin member 17 mounted on the base 14. The pin member at its bottom end is formed at one side with a downwardly extended ear 18, the bottom portion of which is half round, also as best shown in Figure 3. The ear 16 and ear 18 are formed with registering openings.

Preferably, a plate member 19 is transversely arched so as to extend partially around the pin, and through the opposed end portions of this

member fastening means 20 is extended, that passes through the openings of the ears, and serves as a pivot member.

By reason of this construction, it is seen that the pin member 17 mounted on the base can be angularly positioned, at selected angles relative to the upstanding base. The plate member 19 serves to provide resistance to free pivotal movement, so that when the pin member is adjusted to the desired angle, it will remain at said angle even when struck forcibly by a ring thrown by a player.

The short pins 13 are formed exactly in the same manner as the long pins, differing only to the extent that the pin members 21 of the short pins are, of course, shorter.

Preferably, the top of each pin is formed with an enlarged rounded dome 22.

The game board can be supported in an elevated position above a floor or other supporting surface, legs 23 removably mounted in the under side of the game board 5 being provided for this purpose. Or, if it is desired to place the game board flat on a floor, legs 23 can be removed. Another possibility is to remove one of the legs, this permitting the board to be disposed in an inclined plane.

Each pin position is marked with a suitable number as shown at 24. I believe it is well within the spirit of the invention to use names instead of numbers, or both, as desired.

In playing the game, rings 25 would be used. These are adapted to be thrown so as either to encircle any of the pins 12 or 13, or so as to be received in pocket 7.

I believe that from the description which has been provided, and by reference to the drawing, it will be readily apparent that the game board which I have devised is unusually versatile. It can be used either indoors or outdoors, elevated above the floor, placed flat on the floor, or inclined. The locations of the pins 12 and 13 can be varied in many ways. For example, if all the long pins 12 are disposed in the inner series of openings 11, access to the pocket 7 becomes more difficult. Any number of the pins can be used, so that both the outer and inner series of openings can be utilized to support the pins, or either of these series can be used, with no pins being disposed in the other series. Another possibility is to remove selected pins from both series.

Games can be played in which both pocket and pins play a part, and other games can be played in which the pocket alone is used, or the pins alone used. Additionally, the angularity of all or selected pins can be varied selectively.

Purely for the purpose of supplying examples of games which might be played with the board, the board can symbolize a school, movie studio, or the like, with the pins representing rebellious students, or movie stars. Many other games can suggest themselves.

As may be noted by reference to Fig. 1, in accordance with the invention there are two annular series of pin-receiving openings in one of which the short pins are mounted and in the other of which the long pins are mounted, these being concentric with the center opening. Each opening of the inner annular series is aligned radially of the center opening with a particular opening of the outer annular series. For example pin position 1 is aligned radially with pin position

9, and pin positions 8 and 16 are also radially aligned. This is carried out throughout the game board. By reason of this arrangement, a short pin is paired with a long pin, and a long pin can be adjusted angularly toward the short pin so as to reduce the space surrounding the dome of the small pin to increase the difficulty of encircling the small pin with one of the rings 25. This angular adjustment of the upper portions of the respective pins toward and away from each other has a direct effect upon the relative difficulty of playing the game, and the difficulty of playing the game can be reduced or increased within a wide range.

With further reference to this characteristic of the structure, it may be noted that the vertical bases of both the short and the long pins are of equal height, the distance in the overall length of the respective pins being varied by variation of the length of the upper portions of said pins. This arrangement is one which permits angular adjustment of the longer pins to an extent which will swing the domes of the longer pins across a substantial space to an extent where they can even be brought into direct engagement with the domes of the short pins with which they are radially aligned, despite the substantial spacing between the respective concentric annular series.

What is claimed is:

A device of the class described including a board formed with a plurality of concentric, spaced apart, annular series of pin-receiving openings, each opening of a series being aligned radially of said concentric series with an opening of each other series; short pins removably mounted in the openings of one series for rotary adjustment; and longer pins removably mounted in the openings of a different, adjacent series for rotary adjustment, said short and longer pins each including a vertical base seated in a selected position of rotary adjustment in one of the openings, the bases of all the pins being of equal length, a pin member hingedly connected to said base, the pin members of the longer pins being substantially longer than those of the shorter pins, and being of a length to cause the upper ends of the longer pins to engage or be positioned closely to the upper ends of the respective shorter pins with which they are radially aligned when adjusted angularly upon their hinges toward the shorter pins, and an arcuate plate affixed to the base and extending beyond the connection of said member to the base to straddle the pin member, said plate frictionally engaging the pin member in positions to which said member is swung for holding the pin member in positions of angular adjustment relative to the base.
